BAFFLE ASSEMBLY FOR AIR CIRCULATOR

Edward O. Wehmeyer, St. Louis, Mo.

Application September 26, 1941, Serial No. 412,421

5 Claims. (Cl. 230—274)

This invention relates to improvements in baffle assemblies for air circulators, the elements of novelty and features of design being particularly but not solely applicable to embodiment in small portable or semi-portable room-air circulator units.

There are prevalently widely sold, substantial numbers of air circulator units of the types characterized by a propeller fan operatively connected to a vertical shaft motor, with a generally cone-shaped baffle disposed across the discharge stream of the fan. Such baffles are employed with the general object of deflecting the air discharged by the fan, in a horizontal and partly downward direction throughout a given zone of the room or other space in which the circulator is utilized.

It has been discovered, as a result of exhaustive tests with various means for determining direction and velocity of air movement, that the conventional baffles employed in units of the type noted, are relatively inefficient, and fail in great measure in their intended function because of the fact that the air deflected by the conventional baffles is so directioned that a large proportion thereof abruptly engages the floor or similar horizontal surface in a zone not far outwardly of the unit. This results in a "rebound" effect, and is undesirable since such effect impairs the effective coverage or area of spread of the air stream. The outward movement of such stream with conventional baffles is thus considerably impaired by unwanted turbulence, the tendency to drive dust or other foreign particles from the floor up into the room, and very importantly, operates to detract from the maximum cooling effect of the unit which would be obtained but for the noted shortcoming. It is accordingly a major object of the invention to improve the direction or trend of air stream discharged from units of the noted type, although it will of course be understood that the improved shaping and design of baffles constituting an important feature of the invention, are not by any means restricted to units of the type selected for exemplary illustration.

A further object of the invention is attained in an improved design and construction of baffle which, besides attaining the advantages in better air distribution above noted, serves markedly to reduce the axial dimension or depth of such baffles, thus minimizing height and in many cases weight and space requirements in general, of air circulator units.

Yet another object of the invention is attained in an improved means for varying at will, as by manual adjustment, the angle of deflection of

the annular air stream emitted by circulator units of types employing a baffle with a propeller type fan or the like, such facilities for angular variation of the air discharge stream, enabling this adjustment without interference with the full advantages noted in the preceding objects.

Further objects, somewhat ancillary to those heretofore noted, may be stated as attained in a greater spread or wider distribution, of the air impelled outwardly of a fan and baffle type circulator; the elimination of resonance effects sometimes heretofore experienced, particularly with metal baffles for the general purpose noted, and the provision of improved means for adjusting a baffle element or a part of the baffle assembly, for varying the distribution of air by the baffle, in and through different vertical zones above the floor, desk or other support for the unit.

The foregoing and numerous other objects will more clearly and fully appear from the following detailed description, when considered in connection with the accompanying drawing, in which:

Fig. 1 is a side elevation, somewhat reduced in proportion, of a portable room air circulating unit to which the present improvements are applied;

Fig. 2 is a vertical sectional elevation of the motor, fan, a portion of a housing thereabout, and a baffle, particularly showing the relation of the fan to the baffle;

Fig. 3 is a vertical sectional elevation of a somewhat modified baffle structure;

Fig. 4 is a vertical sectional elevation of a further modified form of baffle with which is provided means for adjusting certain of the elements of the baffle structure in order to vary the angle of air delivery from the baffle;

Fig. 5 is a fragmentary sectional elevation showing certain of the parts of Fig. 4 in a different adjusted position, and

Fig. 6 is an enlarged section, in a vertical plane, of a marginal portion of the baffle shown in Fig. 2, in order better to illustrate the sectional curvature of a marginal portion of the baffle, and the function of such portion in deflecting parts of the air stream.

Proceeding now to a description of parts by characters of reference to the drawing, it will be noted that one of the many advantageous embodiments of the present improvements is in a small portable unit for circulating air in a room or other enclosure, and in which unit a propeller type fan is employed, rotatively mounted on the shaft of a vertically disposed motor, with a baffle or the like adjacent and above the fan. In such

a unit the discharge of air is effected peripherally of the unit in the regions of the margin of the baffle, and the annular discharge stream emanating from the baffle is projected horizontally in part, yet given a somewhat upward or optionally a downward trend.

The small unit selected to exemplify an installation of the kind noted includes a pair or more of vertical frame members 10, each of generally rectangular form, formed of a tubular stock, and provided with a somewhat widened floor engaging portion 11. One side of the unit only being shown, there appears in Fig. 1 only a single such structure 10-11. In this unit, a fan actuating motor 12 is carried by a transverse portion 13 of a somewhat cylindrically shaped enclosure 14. The latter is provided with a patterned arrangement of air-inlet openings, for example, such as shown at 15. The structure 14 thus serves, through the element 13, to carry the motor 12, the latter being fixed in position in the element 13 as by screws or the like 16. The housing element 14 is, in turn, so arranged that it derives its primary support from the vertical elements 20, being the riser members at each side of the supporting frame 10, screws 21 serving to position the housing 14 to the members 20.

Supported close to, and yet just above the housing 14, is a baffle structure indicated generally at 22. As will be seen from Fig. 2, showing certain of the parts in section and somewhat enlarged, the baffle structure 22 is of a diameter, in case it be of circular form, somewhat approximating the diameter or greatest cross dimension of the housing 14. Located just within and below the upper margin of the housing 14 is a multi-blade propeller type fan which may be of any suitable or conventional form, and is indicated generally at 23. The fan is provided with a hub structure 24 secured as by a set screw 25 to the motor shaft 26. A convenient and simple means for mounting the baffle structure 22 in assembly, consists of screws 30 one of which extends at an appropriate height, through each of the riser elements 20 of the side frames, and into engagement with the baffle structure.

Proceeding now to a description of the novel features of the baffle structure such as 22, the latter is shown in Fig. 2 as consisting of a single piece of wood, plastic material or other non-metallic and non-resonant substance. If constructed of wood, or even of a synthetic plastic, the element 22 may be and preferably is formed of a plurality of laminations (not shown) adhesively secured together and compacted as by hydraulic pressure into what is in effect a single block or unit. The baffle forming block is preferably thus integrated, unless formed of a single piece of wood for example, prior to contouring.

The contouring or shaping of the baffle particularly the surface thereof confronting the fan and constituting the major or primary baffle surface, as well as the perimeter or marginal portion bounding such surface, go to the essence of the present invention. The prevailing practice has heretofore been to construct, for economy, baffle elements for this general purpose, of sheet metal pressed to a frusto-conical or similar shape. Such baffles are prevalently of such form as to present a partly conical surface as the major baffling area, and are further characterized by the usual sharply angulate periphery or corner. Both formerly prevailing practices make for an adverse and unwanted air deflecting effect, namely, the tendency of the annular streams de-

flected outwardly of the baffle, to proceed along no uniform outward course, but generally within a zone six to eight feet outwardly of the unit to strike the floor or other support for the unit and rebound therefrom. It has been found by an exhaustive series of carefully conducted experiments, that this effect can be entirely eliminated by convexly curving, on a substantial radius, the surface of the baffle which is first or primarily engaged by the discharge stream of the fan. The adverse effect above noted is further obviated and the spread of the air stream delivered beyond the baffle is still further enhanced, by avoiding any semblance of a sharp or distinctly angulate corner at the margin of the primary baffling surface, specifically by providing a rounded margin or edge of the baffle in this zone. The convexity of the margin is, however, due to a sectionally arcuate shaping on very much smaller radii than is the surface of the primary baffling area.

It will be obvious that the exact radii of curvature to be given, first, the primary baffle surface, and secondly, the baffle margin, will depend somewhat on the diameter of fan, hence the diameter of the unit with which the baffle is employed.

The experiments conducted clearly indicate, however, that the curvatures noted in improvement of the pattern of delivered air stream are critical within limits to produce the desired effects. For example, an optimum relation of radius of sectional curvature of the primary baffling surface to the diameter of the fan, has been found to lie between limits of one and one-half to three times the diameter of the fan, best results having been obtained when this ratio is slightly greater than 2:1. To provide a specific example, with a 12" propeller and a baffle element such as 22 only slightly larger in diameter than the propeller, a radius of twenty-five and one-half inches such as indicated by line 32 drawn on center 33, will produce the most favorable results.

Further in reference to the example selected for illustration, it has been found that the radius of sectional curvature of the margin 34, when employed in a baffle approximating the diameter of a 12" fan, such radius of curvature, taken say on line 35, produces the best results when it is of the order of five-eighths inch, and with fans of ordinary and usual diameters, a lower limit of slightly less than one-half inch, and an upper limit of one inch for this radius are regarded as practical.

It has been found after repeated experimental trials, that the unusually shallow construction of baffle characterizing the present improvements serves not only to produce an improved pattern of the annular air stream delivered from the unit, but effects a substantial reduction in the necessary vertical dimension or headroom requirement of the functional portions of the assembly. This feature makes for a smaller, more compact unit than would be required according to heretofore prevailing theories of design.

It is important to note that while the baffle structure 22 is shown as being of appreciable depth, such proportioning is in fact only to provide a greater area of bearing between the riser elements 20 of the frame, and the vertical side surfaces of the baffle. Actually, the functional portion of the baffle need and does not extend beyond the zone indicated by the line 40 in Fig. 6, or more particularly expressed, the baffle need not be of greater depth than is necessary for the

surfaces characterized by the slopes above described, to reach the vertical. As a general criterion it may be noted that the depth of the functional portion of the baffle need not exceed the depth of the fan itself. In the case of many prevailing types of three or four blade propellers, the depth of the fan may be of the order of 2", while a baffle structure bearing about the space relation to the fan as shown by Fig. 2, need not exceed a depth, through its functional portion, of one and one-fourth inches.

It results from the relatively shallow form of baffle utilized according to present design, that the baffle can and preferably is disposed relatively close to the fan not only for the purpose of enhancing or improving the pattern of the air stream delivered from the unit, but enabling a further reduction in overall vertical dimensional requirements. Some slight spacing of the baffle beyond the fan is desirable; but it may be noted that the proximity of baffle and fan are such that no part of the baffle need be spaced from the fan a distance greater than two or three inches. A two inch spacing of the most widely separated portions of baffle and blade, near the peripheries of the fan and baffle respectively, has been found entirely adequate in assemblies employing fans of the usual diameters.

Assuming a rounded marginal contour such as 34 of the baffle of Fig. 2, it should be noted that, although a distinctly sectionally curved primary baffle surface such as indicated at 41, is preferred, a distinct improvement over the strictly conical or even concave baffles heretofore used, may be attained by contouring the surface 41 from its center zone 42 so that a section thereof between zones 42 and 34 lies along a straight line. Whether this half section be identified with either a straight or curved line, the slope thereof being fixed, it should not greatly exceed twenty degrees to a plane parallel to the planes of revolution of the propeller. Best results are found to obtain when this slope is of the order of values between ten and twenty degrees, say fifteen degrees as an optimum.

Following the foregoing description of structure and design of baffle, no extended discussion of effect in operation is regarded as necessary, but it may be noted for completeness that the air drawn from below and into the housing 14 by revolution of the fan 23 is driven outwardly along the lines of the arrows of Fig. 2, this discharge stream from the fan first and primarily impinging the surface 41 of the baffle. The action of this annular stream of air upon reaching the rounded corner portion 34 is of great importance. It is a preference that the sectional rounding or contouring of the portion 34 be carried through say ninety degrees of arc or from the zone indicated at 43 (Fig. 6), to the line indicated at 40, the intermediate half of this angle of contouring, being the angle indicated in Fig. 6, is however regarded as the more active portion of the convex margin. While the air stream emanating from this zone is of appreciable depth, it will nevertheless proceed with fair uniformity in a generally tangential direction as indicated by arrow 44, the greater part of the tangent stream of air leaving the baffle at point 45. The result of the contouring, both of the surface 41 and of the margin 34, is that the discharge stream is characterized by a minimum of turbulence, and by only a negligible tendency to engage and rebound from the subjacent supporting surface such as a floor. The stream will nor-

mally proceed outwardly and somewhat upwardly after the manner of an inverted, relatively flat parasol.

Although the non-metallic baffle 22 of Fig. 2 offers certain advantages, it is distinctly within the purview of the present invention to construct a baffle say of pressed metal, and hollow in form. Such a construction is shown by Fig. 3, the contouring of the active baffle surface portions of the structure of Fig. 3 being in all important respects the same as that heretofore described. In this modification, the center zone of the baffle is indicated at 50 and the convex, primary baffling surface at 51, while the convex perimetral margin corresponding to the margin 34 of Fig. 2 is indicated at 52. For appearance and also to minimize resonance, a pan-like cover element 53 may be provided and secured to the body of the baffle 54 as by screws 55. The function and several aspects of curvature of the structure of Fig. 3 may be considered identical with those described in connection with baffle 22.

In order to provide facilities for control of both spread and angular direction of the annular stream discharged from the unit, a further modification of baffle structure is shown by Figs. 4 and 5. In Fig. 4 the baffle structure is characterized by a lower, outwardly convex, major or primary baffling element indicated at 60. The outer surface provided by the element 60, across the stream of the fan, is marginally bounded by a convex perimeter 61, the curve characteristics of which are or may be the same as described in respect to the portion 34 of baffle 22. The portion 61 extends outwardly to form a cylindrical wall of the baffle body, indicated at 62, and the baffle is provided with a top closure 63 secured to the body as by screws 64.

In this modification adjustment of slope and spread of the discharge stream is effected by a movable secondary baffle in the form of an annulus 65. This element is preferably formed of a metal stock of circular section, and to enclose the ring 65 when in a retracted or non-baffling position, there is provided an inverted annular recess 66. This recess is of a size snugly to accommodate the ring 65, so that with the latter in its retracted position it will appear that the element 60 presents a baffling surface which has identical air-deflecting characteristics with the surface 41 of baffle 22 and the surface 51 of baffle 54. In cases where it is desired to confine the spread of the discharge stream of air from the unit to a zone relatively close to the unit, and to project the stream somewhat downwardly from its zone of discharge, the secondary baffling surface constituted by ring 65 may be lowered to the desired degree to bring it into the discharge air stream. Facilities for such adjustment consist, in the example illustrated, in two or more, preferably four, supporting studs or posts 67. These are normally vertical as shown, and may be threaded into or extend through the ring 65 at diametrically spaced points. It is a preference to employ four such studs 67, each thereof being close and parallel to one of the four riser elements 20 of the frame whereby to minimize interference of these parts with the outwardly directed air stream. Arranged diametrically and within the baffle housing 62, is one or a pair of cross pieces 70 each apertured near its opposite ends to receive the upper ends of the diametrically spaced studs or posts 67. Disposed below cross piece or pieces 70 are resilient means, such as a

plurality of compression springs 71 tending to bias upwardly the cross piece 70 and therewith, the posts 67 and ring 65, the arrangement tending at all times to bring the ring to a retracted or inoperative position. Centrally of one or both of the cross pieces 70, if more than one be employed, is a socket member 72 provided with a central depression for the reception of a threaded post 73, the latter being in threaded engagement with a central aperture in a boss 74. The threaded post or stud 73 is provided with a stop member 75 to limit its upward or outward threaded movement. It will be noted that the threaded element 73 extends outwardly through the cover 64 of the baffle and is surmounted by a turning knob or the like 76.

It will have appeared that rotation of knob 76 in one direction will operate to depress, through the socket member, the cross piece or pieces 70 and similarly the studs or posts 67 and the ring 65 to bring the latter into selectively depressed positions in the peripheral portion of the outgoing air stream, the deflecting effect of the ring being illustrated by the section of Fig. 5. When it is desired again to retract and render inactive the secondary baffle surface identified with ring 65, the knob 76 is obviously actuated in the opposite direction and the springs 71, theretofore compressed, serve to lift the cross piece 70 and therewith the posts 67 and ring 65.

It will have appeared that the several structures described serve fully to attain each of the several objectives hereinabove set forth, and others implied from the description and function of elements.

For brevity the improvements have been described in connection with a relatively small portable or semi-portable air circulating unit. This should however not be taken as restrictive of application of the principles of the invention. It should further be noted that wherever limits of radii of curvature, or angular extent or spacings are specified in the description, these limits should be considered applicable primarily to units employing fans of the order of six to twenty inch diameters, without restriction as to units employing larger or smaller size fans.

Many changes in the parts and their described relations are of course possible within the intended scope of the claims hereunto appended.

I claim as my invention:

1. In an air circulating assembly, a rotatable air impeller, means for actuating the impeller, a baffle structure arranged transversely across the impeller discharge stream, the baffle structure including a fixed central portion and a peripheral portion movable toward and from the impeller and in a direction along the impeller axis for varying the angle of discharge of the air by the baffle.

2. In an air circulating assembly, a rotatable air impeller, means for actuating the impeller, a baffle structure arranged substantially across the

impeller discharge stream, the baffle structure including a fixed main baffle portion, an auxiliary baffle portion in the form of an annulus located near the perimeter of the main portion, and means for adjusting the annulus in an axial direction with respect to, and to different operating spacings from the impeller.

3. The combination and arrangement of parts as recited by claim 2, further characterized in that the annulus is convex in section and the outer margin of the main baffle portion is also of convex section.

4. In an air circulating assembly, a rotatable air impeller, means for actuating the impeller, a baffle structure arranged substantially across the impeller discharge stream, the baffle structure including a fixed primary baffle portion characterized by a central area of slightly convex sectional contour, and of circular section in planes parallel to the plane of rotation of the impeller, the primary deflecting surface of the baffle terminating peripherally in a convexly rounded margin, which margin thence extends sharply away from the impeller, the baffle including an auxiliary baffle ring adjustable into different planes generally parallel to the plane of rotation of the impeller, the baffle structure being hollow and provided with supporting studs for said ring, projecting from the interior to the exterior thereof into supporting engagement with the ring, a cross piece located diametrically of and within the baffle structure and secured to said studs, spring means below the cross piece and tending therethrough to urge the ring to a retracted or inactive position, a screw threaded element operatively connected, for adjustment purposes, to the cross piece, and a member disposed for manual actuation exteriorly of the baffle for adjustment of said ring through said screw threaded means.

5. In an air circulating assembly, a rotatable air impeller, a baffle structure located adjacent the impeller and being characterized by a substantially uniform convex contour of its major baffling area, and a distinctly convexly rounded margin bounding the major baffling area, the baffle including an auxiliary baffle ring near the periphery of the major baffling area, and adjustable into different planes generally parallel to the plane of rotation of the impeller, the baffle structure being hollow and provided with supporting studs for said ring, projecting from the interior to the exterior of the baffle structure into supporting engagement with the ring, a cross piece located diametrically of and within the baffle structure and secured to said studs, spring means below the cross piece and tending therethrough to urge the ring to a retracted or inactive position, a screw threaded element operatively connected, for adjustment purposes, to the cross piece, and a member disposed for manual actuation exteriorly of the baffle for adjustment of said ring through said screw threaded means.

EDWARD O. WEHMEYER.
